United States Patent Office

Des. 181,914
Patented Jan. 14, 1958

181,914

TRAILER

Stephen L. Spencer, Atherton, Calif.

Application October 15, 1956, Serial No. 43,354

Term of patent 14 years

(Cl. D14—3)

FIG. 3

I claim:

The ornamental design for the trailer, as shown and described.
